W. A. Eudaly,

UNITED STATES PATENT OFFICE.

WILLIAM A. EUDALY, OF CINCINNATI, OHIO.

BRICK AND TILE KILN.

SPECIFICATION forming part of Letters Patent No. 295,864, dated March 25, 1884.

Application filed February 4, 1884. (No model.)

To all whom it may concern.

Be it known that I, WILLIAM A. EUDALY, a citizen of the United States, residing at Cincinnati, in the county of Hamilton and State 5 of Ohio, have invented certain new and useful Improvements in Brick and Tile Kilns, of which the following is a specification, reference being had therein to the accompanying drawings.

10 My invention relates to improvements in kilns for burning brick, tile, and other ceramic ware.

The object of my invention is to construct a double kiln in such a manner that a perfect combustion of the gases and fuel can at all times be insured, and at the same time an equal distribution of the heat attained; and to this end my invention consists in the construction of a 15 double kiln the partition or dividing wall of which is provided with vertical flues, which form chimneys, and with horizontal flues controlled by dampers, by which means the kiln can be readily changed from a double kiln to two separate and distinct kilns, each having 20 its own furnaces, and provided with flues or chimneys in the outer and in the partition wall, which are adapted to be controlled by dampers, so that the heat can be directed to any particular portion of the kiln.

25 My invention consists, further, in placing the chimneys or exit-flues within the air-chambers, which supply air to the eye or throat of the furnace, so that the waste heat from the kilns can be utilized in heating the air prior 30 to its being mingled with the gases of the fuel.

35 My invention consists, further, in certain details of construction, which will be fully described hereinafter, and pointed out in the claims.

40 Figure 1 is a horizontal sectional view of a kiln embodying my invention on the line $x-x$ Fig. 2. Fig. 2 is a vertical sectional view on the line $x'-x'$ of Fig. 1. Fig. 3 is a similar view on the line $y-y$ of Fig. 1. Fig. 4 is a vertical 45 sectional view on the line $y'-y'$ of Fig. 1.

A A are the end walls of the kiln, and B B the side walls, while C indicates the center or partition walls.

50 D D are the furnaces, the throats or eyes of which are formed in the side walls of the kiln, and open into the fire-bags.

The furnaces, together with the throat or eye of the kiln-wall and the fire-bags, are essentially of the same construction as those shown, described, and claimed in an application for 55 a patent filed by me January 31, 1884, Serial No. 119,375, and need no further description here. The floor of the kiln is composed of a series of solid benches of masonry, E, which extend from the ground to the level of the 60 floor of the kiln, and running the entire width of the kiln.

F F indicate the other portions of the kiln-floor, which consist of brick or tile laid a short distance apart, so as to communicate with the 65 chambers or flues G, which also extend the entire width of the kiln, and open into flues or chimneys H in the partition-wall C, and also into flues or chimneys I in the side walls. These flues G are adapted to be closed by a 70 damper, K, operated by a rod, a, passing up through the partition-wall C, and by which means the heat can be confined to one compartment of the kiln or distributed into the adjacent kiln. The flues G also communicate 75 with the vertical flues or chimneys H by means of the diagonal flues or ducts L, which, when the dampers K are closed, convey the smoke, &c., to the flues H. The flues F also communicate with the chimneys or flues I, located in 80 the front wall, said chimneys being surrounded at their lower ends with the air-chamber b, and by which means the air in the chamber is heated by coming in contact with the walls of said chimneys or flues before it is mingled 85 with the gases of the furnace. The flues or chimneys H and I are both provided with dampers, by which the direction of the draft can be changed, so that the heat can be thrown into all parts of the kiln.

90 It will be noticed that the construction of the furnaces and flues is the same on both sides of the partition-wall, and that the kilns can be made to operate independently of each other by closing the flues G by means of the 95 dampers or valves K; but when it is desired to drive off the water-smoke of the adjacent kiln, or burn the lower courses of brick in the adjacent kiln to a greater extent, the dampers K are opened and the dampers in the chimneys H 100 and I closed. This will cause the heat or products of combustion to pass through the flues

G under the partition-walls C, and be distributed through the wares in the adjacent kiln, as indicated by the arrows 1 in Fig. 2. It will also be noticed that when it is desired to burn 5 the wares in the lower corners of the kiln nearest the furnaces, that, by closing the flues G and the chimneys H and opening the drafts in the chimneys I, the heat will be drawn down to that portion of the kiln, as indicated by the 10 arrows 2 in Fig. 2; and, furthermore, if it is desirable to concentrate the heat in any particular portion of the kiln, this can be readily done by leaving the flues and chimneys open at that point, and closing all other ports 15 of egress. By this construction and operation of a brick-kiln, the man in charge of the kiln can have complete control over all portions of the kiln, and thus insure a uniform burning of all the bricks contained therein.

20 Having thus described my invention, what I claim, and desire to secure by Letters Patent, is—

25 1. A kiln provided with a partition-wall in which are located chimneys communicating with and extending from the continuous flues at the bottom of the kiln only and leading to above and beyond the kiln-roof.

2. In a double kiln, continuous flues situated in the bottom of the kiln, and running under the partition-wall, and adapted to be divided at the partition-wall by dampers or cut-offs, as set forth. 30

3. In a kiln of the character described, the continuous flues, extending from side to side of the kiln, in combination with the partition-walls C and dampers K, as set forth. 35

4. In a kiln-wall, air-chambers situated at the sides of the eye of the kiln, and within the walls of the kiln, arranged as described, so that the escaping heat from the kiln is made 40 to pass through said air-chambers by means of chimneys situated within said air-chambers.

5. In a brick-kiln, the combination of the flues G, provided with dampers K, with the lateral or diagonal flues L and chimneys H, 45 as set forth.

In testimony whereof I affix my signature in presence of two witnesses.

WILLIAM A. EUDALY.
